UNITED STATES PATENT OFFICE

2,194,688

WASHING MACHINE

Agatha K. Bremer, New Washington, Ohio

Application August 16, 1937, Serial No. 159,368

4 Claims. (Cl. 68—132)

A purpose of this invention is to provide a washing machine convenient for saving the trouble of hand washing when only a few small articles are washed at a time; and aside from that general purpose, the objects of the invention are to provide an improved oscillating blade construction for impelling and reversing the movement of the washing fluid in horizontal directions around the axis of the device, and both up and down on each stroke and to divide the fluid currents and alternately produce suction and pressure conditions in opposite directions.

A further object of the invention is to form the body or receptacle part of the device as a small kettle or stove pan with handles wherein the articles to be washed may, with convenience, be boiled prior to or during the application of power through the lid unit which carries the movable operating parts of the construction.

With these objects in view the construction is made as illustrated in the drawing wherein:

Figure 1 shows the device in transverse vertical section.

Fig. 2 is a fragmentary horizontal section taken on the line 2—2 of Fig. 1.

Fig. 3 is a detail in vertical section taken on the line 3—3 of Fig. 1.

Fig. 4 is a detail vertical section taken on line 4—4 of Fig. 1.

Fig. 5 is a diagram showing surface variations of one of the impeller blades indicated comparatively in the planes A, B, C, and D designated in Figs. 1 and 5.

Fig. 6 is a fragmentary sectional detail showing how the lid construction is depressed around the crank bearing to form a lather receiving pocket. The suds may pass through vent holes in the lid, whereby the condition of the washing fluid may be ascertained without removing the lid.

The receptacle part of the construction is a pan or kettle and may be about a foot in diameter and provided with handles on each side. The rim of the kettle forms a rest for the lid and the latter is provided with clamps whereby the lid may be drawn tightly into place on the rim. A crank is journaled in the center of the lid and carries the agitating or paddle construction. The latter is preferably an aluminum casting having a pair of blades of different areas and form. The smaller one is curved to alternately impart downward and upward thrust on the contents of the receptacle, as the blade oscillates. The other, larger blade is curved to impart outward and inward thrusts and has a diagonal bend between opposite corners, and produces a corresponding

alternate diagonal thrust on the content of the machine in opposite directions with the purpose of producing opposed currents whereby alternating vacuum and pressure actions of the fluid on the material being washed are effectively attained.

As detailed in the drawing, the kettle or receptacle part of the construction is indicated at 1 with handles 2 on opposite sides. Rim 3 of the kettle is formed to receive a cast aluminum lid 4, 10 and the latter has ears 5 integral or riveted thereto which form pivot supports for lid clamping members 6, the pivots being indicated at 7. The clamping members 6 support pins 8 upon which are pivoted rim clamping claws 9. This forms a 15 toggle connection whereby the claws are caused to draw the lid tightly down against the rim. The center part 10 of the lid forms a substantial bearing for a crank 11. The end 12 of the crank passes through the bearing and carries a limit- 20 ing collar 13 above the bearing, and a nut 14 at its lower end which serves to hold the paddle casting 15 on the squared part 16 of the crank. The lid is preferably formed with a central depression 17 around the upper end of the bearing 10 25 which has vent holes 18 allowing suds to pass therethrough as indicated in Fig. 6. These vent holes serve to minimize possible leakage at the rim by allowing for the escape of steam and incidentally indicate the condition of the washing 30 fluid.

The paddle casting 15 includes the opposite vanes or blades 19 and 20 which differ as to area and form, and each is provided with a plurality of openings 21 countersunk on each side for the 35 purpose of increasing the velocity of fluid passing therethrough under the actions of differential pressures on opposite sides of the paddles. Each blade is strengthened by vertical ribs 22 and 23 extending between the rows of perfora- 40 tions.

Blade 19 is curved at its lower part around a radial horizontal axis to form a sweep 24 and blade 20 has a diagonal bend along line 25 which divides the blade into two relatively inclined 45 areas 26 and 27 whose vertical elements are respectively inclined in opposite directions with respect to a radial plane. Blade 20 is also curved at its outer end around a vertical axis to form a marginal sweep 28. Due to the variations of surfaces and forms of the blades, they are well adapted to produce variable direction effects on the washing fluid.

In the operation of the construction, aside from its use as a boiler, clothes are washed by 55

oscillating the crank; the paddle, therefore, works back and forth.

The two blades differ in form for the purpose of producing the maximum agitation and suction effects in various directions. Blade 19 throws, or drags, the washing fluid back and forth in an annular and outward direction and up and down, the bottom of the blade being somewhat curved for the latter purpose. Also blade 20, of different form, serves to force the fluid outwardly and also inwardly as it oscillates, due to the curvature on its outer edge and the opposed inclination of its two surfaces 26 and 27. These impart alternate diagonal impulses to the washing fluid. Thus alternate pressure and vacuum effects are produced in various directions, making a rapid and thorough washing action. Such action is further assisted by the relative flow of the liquid through the countersunk perforations 24, with reference to the blades and the clothes which are drawn back and forth by the blades.

I claim:

1. A washing machine of the class described comprising a receptacle and a lid attached to said receptacle, a crank centrally journaled in said lid, a paddle secured to the lower end of said crank and comprising a pair of blades, one of said blades having a radially extending portion warped on a diagonal line with reference to the axis of said receptacle to form oppositely inclined surfaces on each side of the blade for the purpose of thrusting contents of the receptacle diagonally upward and downward through rotation of the blade in either direction, and one of

said blades being bent about a vertical axis to form a sweep at its outer margin.

2. A washing machine comprising a receptacle body and a lid with attaching means for securing the lid to the body, a crank centrally journaled in the lid, a paddle secured to the lower end of the crank and comprising a pair of blades differing in area and form, one of said blades having its lower end curved around a horizontal radial axis while the other blade has its outer edge curved around a vertical axis, a diagonal bend in said last-mentioned blade with oppositely inclined surfaces on each side of said bend.

3. In a washing machine, a vertical shaft, a pair of paddles on said shaft, one of said paddles comprising a radially disposed blade bent about a horizontal axis to form an inclined sweep at its lower margin, and the other of said paddles comprising a radially disposed blade bent about a vertical axis to form an inclined sweep at its outer margin, said blades being spaced apart with respect to the axis of rotation to provide a central open area between them and said sweeps being located to follow each other in the same horizontal plane.

4. In a washing machine, a vertical shaft, a paddle on said shaft comprising a radially disposed blade having a warped body portion made up of oppositely inclined vertical elements at opposite sides of a diagonally inclined dividing line and having an end portion bent about vertical lines to form an inclined sweep at its outer margin.

AGATHA K. BREMER.
